(57) **CLAIM**

The ornamental design for a lifting apparatus, as shown and described.

DESCRIPTION

FIG. 1 is a perspective view of a lifting apparatus showing the new design.

FIG. 2 is another perspective view of the lifting apparatus of FIG. 1.

FIG. 3 is still another perspective view of the lifting apparatus of FIG. 1, shown in use.

FIG. 4 is yet another perspective view of the lifting apparatus of FIG. 1, shown in use.

FIG. 5 is a side view of the lifting apparatus of FIG. 1.

FIG. 6 is a front view of the lifting apparatus of FIG. 1.

FIG. 7 is a rear view of the lifting apparatus of FIG. 1.

FIG. 8 is a top view of the lifting apparatus of FIG. 1; and, FIG. 9 is a bottom view of the lifting apparatus of FIG. 1.

All of the broken lines in the accompanying drawings illustrate environmental structure and form no part of the claimed design.

1 Claim, 4 Drawing Sheets
